UNITED STATES PATENT OFFICE.

HARRY A. PYLE, OF ST. LOUIS, MISSOURI, ASSIGNOR TO LIGGETT & MYERS TOBACCO COMPANY, OF NEW YORK, N. Y., A CORPORATION OF NEW JERSEY.

CARTON OPENER.

Application filed May 21, 1923. Serial No. 640,396.

To all whom it may concern:

Be it known that I, HARRY A. PYLE, a citizen of the United States, and resident of city of St. Louis, in the State of Missouri, have invented a certain new and useful Improvement in Carton Openers, of which the following is a specification.

My invention relates to an opening device or cutter especially adapted for opening cartons such as the corrugated paper cartons of various sizes used for packaging various commodities, and also useful for other purposes where some or all of the conditions are similar.

15 The invention comprises, broadly described, a shank provided at one end with a handle and at the other end provided with a blade, and preferably a blade having a plurality of cutting edges including 20 a cutting edge on the outward end, and a guard or guide adapted to engage one portion of a carton, such as the top face, and properly guide and locate the blade to cut through the walls of the carton at a suitable 25 distance below the top. Desirably the blade is detachably connected to the shank, and desirably also the guard or guide plate is detachably connected and arranged to hold or assist in holding the blade in position. Desirably also the tool is devised so 30 that thin, flat cutting blades, such as safety razor blades of suitable sizes may be used as the cutting elements, although of course special cutter blades may be provided, particularly adapted for the present purpose.

35 The characteristics and advantages of the invention are further sufficiently explained in connection with the following detail description of the accompanying drawings, 40 which show one representative embodiment of the invention. After considering this, persons skilled in the art will understand that many variations may be made within the scope of the invention, and I do not 45 limit myself to details except as claimed.

Figure 1 is a side elevation of a complete carton cutter, embodying the invention in one form.

Figure 2 is a perspective view of the separated parts shown in approximately proper 50 relation to each other as in process of assembly.

Figure 3 is a perspective view illustrat-

ing the manner of using the tool in opening a carton.

Although the main or handle portion of the tool may vary considerably in some cases, desirably it comprises a shank 1 of suitable metal, and desirably the outward portion of the shank has a flat face as at 60 2, or the shank may be of square cross section as shown. One end of the shank is fitted into a suitable handle 3, and the other end portion 4 of the shank is desirably somewhat offset from a part near the handle, for instance, by providing the shank with two curvatures 5 and 6 so that the outward portion 4 is parallel to the handle portion. This is for the purpose of bringing the cutter approximately in line with 70 the center of the handle.

A cutter or blade 7 is located on the outer portion of the shank. Desirably this blade is of very thin material of suitable composition to receive and hold a sharp 75 edge, such as suitable tool steel, or a steel such as safety razor blades are made of, and the cutter may in some cases be a safety razor blade of suitable size. Desirably the blade has cutting edges 8 and 9 on opposite sides, and desirably also the outer end is formed with a cutting edge 10, and in some cases it is desirable to make the corners 11 at one or preferably both. ends of the blade, square and sharp. When 80 special blades are provided they may be made in the form shown in the drawings with cutting edges 8 and 9 on opposite sides and cutting edges 10 on both ends.

85 The cutter or blade 7 is desirably detachably connected to the shank, and this connection may vary considerably. In the present embodiment it comprises studs 12 and 13 inserted in the shank. The stud 13 may be relatively short and permanently 90 fixed in the shank. The stud 12 is desirably longer and may conveniently be in the form of a screw inserted in a threaded hole near the outer end of the shank. The blade is provided with holes 14 adapted to fit over the studs 12 and 13, and when a safety razor blade is used as the cutting blade the studs will of course be located on the shank in accordance with the location of the holes usually provided in the razor blade.

100 A guard or gauge plate 20 is provided to

cooperate with the blade. This is usually of substantially rectangular outline and it is provided with a long or oblong depressed central portion 21, the bottom of which is adapted to rest on the cutting blade and is provided with apertures to cooperate with the studs. The guard plate is detachably secured in position, and in turn retains the blade in position, by a thumb nut or wing nut 22 engaging the screw 12, and having a shank 23 adapted to enter the guard recess 21 and engage against the guard bottom to lock the parts firmly but detachably together. The main flat portion 24 of the guard plate is dimensioned to extend well beyond the cutting edges of the blade, at least at the outer end and along the opposite sides of the blade, and this plate or gauge portion is located parallel to and a suitable distance away from the blade so that when the tool is used, as sufficiently shown in Figure 3, in opening a carton or similar package, some projecting portion of the gauge plate 24 lies upon a surface of the carton such as the carton top, and the blade is then spaced a suitable distance from the top to cut through the carton walls, and partly or completely sever the top, as may be desired. The described arrangement of the blade and gauge plate is such that the tool may be held in either hand and moved about the carton in practically any direction while cutting is done by either side or the outward end edge of the blade. When the blade is provided with sharp corners as above described, the corners are also very effective in cutting the carton or other wrapping material.

When the blade becomes dull it can be easily detached, sharpened and replaced, or repositioned, or another blade inserted, as may be desirable.

The tool is especially desirable for opening carton packages of various tobacco products, or practically any other kind of cartons of the class described.

I claim:

1. A carton cutter, or like implement, comprising a shank, a thin, flat cutting blade thereon having cutting edges at opposite sides of the shank, and a guard plate overlying the blade and having guard-and-gauge portions projecting laterally beyond the cutting edges throughout the length thereof and located in a plane parallel to the blade and spaced substantially therefrom to guide the cutting edges in severing a carton wall.

2. A carton cutter, or like implement, comprising a shank, a thin, flat cutting blade thereon and having cutting edges at opposite sides of the shank and end cutting edge, and a guard plate overlying the blade and having guard-and-gauge members projecting beyond said cutting edges

and located in a plane parallel to the blade and spaced substantially therefrom to guide the cutting edges in severing a carton wall.

3. A carton cutter, or like implement, comprising a shank, a thin, flat cutting blade thereon having cutting edges at opposite sides of the shank, a guard plate overlying the blade and having guard-and-gauge portions projecting laterally beyond the cutting edges, and located in a plane parallel to the blade and spaced substantially therefrom to guide the cutting edges in severing a carton wall, and means retaining the blade detachably upon the shank.

4. A carton cutter, or like implement, comprising a shank, a thin, flat cutting blade thereon having cutting edges at opposite sides of the shank, a guard plate overlying the blade and having guard-and-gauge portions projecting laterally beyond the cutting edges, and located in a plane parallel to the blade and spaced substantially therefrom to guide the cutting edges in severing a carton wall, the guard being superposed upon the blade, and means detachably engaged with the shank and serving to clamp the guard and blade thereon.

5. A carton cutter, or the like, comprising a shank having a flat surface near one end and a handle at the other end, studs projecting from said flat surface, a thin, flat blade of the safety-razor type having side cutting edges and located on said flat shank face and apertured to engage the studs, a gauge plate having a central depressed portion resting on the blade and apertured to receive the studs, the gauge plate having side portions extending beyond the blade edges, and a locking member having screw engagement with one of the studs to detachably secure the gauge plate and blade upon the shank.

6. A carton cutter, or the like, comprising a shank having a flat surface near one end and a handle at the other end, studs projecting from said flat surface, a thin, flat blade of the safety-razor type having side cutting edges and located on said flat shank face and apertured to engage the studs, a gauge plate having a central depressed portion resting on the blade and apertured to receive the studs, the gauge plate having side portions extending beyond the blade edges, and a locking member having screw engagement with one of the studs to detachably secure the gauge plate and blade upon the shank, the outward portion of the shank being offset from the handle portion to bring the blade substantially in line with the handle axis.

7. A carton cutter or the like, comprising a metal shank having a flat surface near one end and a handle on the other end, studs projecting from said flat surface, a thin

blade of the safety-razor type having lateral and end cutting edges, located on the flat shank face and apertured to engage the studs, a gauge plate having a central depressed portion resting on the blade, and apertured to receive the studs, the gauge plate having flat gauge portions extending beyond the blade edges and spaced there-

from, and a locking member having screw engagement with one of the studs to detachably secure the gauge plate and blade upon the shank. 10

Signed at city of St. Louis in the State of Missouri this 15th day of May A. D. 1923.

HARRY A. PYLE.
